LOUVER AND LOUVER BRACKET FOR
FLUORESCENT LIGHT FIXTURES

William P. Crockett, Jr., Chicago, Ill.

Application December 27, 1948, Serial No. 67,519

3 Claims. (Cl. 240—51.11)

1

The present invention relates to a louvre for fluorescent light fixtures. Louvres in general are well known and one of the purposes of a louvre is for the diffusion of the light.

An object of the present invention is the provision of a novel louvre which can be easily and readily applied to the fixture.

Another object of the present invention is the provision of a novel louvre which can be easily manipulated into its final fixed position and out of its fixed position for the insertion or removal of fluorescent light tubes.

A specific object is the provision of such a novel louvre having a hinged arrangement so that it can be easily swung into and out of its fixed position.

Still another object is the provision of a novel louvre which is generally in the shape of a cylinder and as such has fins disposed around the fluorescent light tube.

A further object is the provision of a louvre having a novel construction whereby the above objects are carried out and which has a pleasing appearance.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is a side view of the louvre of the present invention applied to a fluorescent strip box;

Figure 2 is a view from the left of Figure 1 showing the louvre in closed or in its fixed position;

Figure 3 is a view similar to Figure 2 but showing the louvre swung to open position so that the light tube can be inserted or removed;

Figure 4 is an enlarged view taken on line 4—4 of Figure 1 and showing one of the hinged brackets from the side opposite to that of Figure 2;

Figure 5 is an enlarged detail view taken on line 5—5 of Figure 1;

Figure 6 is a view similar to Figure 5, but showing one end of the supporting bracket sprung to position for opening the louvre; and

Figure 7 is a detailed view illustrating an alternate type of pin for securing the louvre in fixed position, and oriented as if taken on line 7—7 of Figure 4.

Referring now in detail to the drawings, Figure 1 shows the louvre as a whole at 12, shown secured to a fluorescent strip box 14. The strip box 14 is ordinarily secured to the ceiling as indicated in Figure 1 and is in the form of an

2

elongated, generally rectangular shape. The details of the strip box 14 itself do not form a part of the present invention and it may suffice to say that the strip box is provided with a pair of sockets 16 which are disposed adjacent to the ends of the box and extending downwardly therefrom. A fluorescent light tube 18 is inserted in the sockets in a conventional manner which is merely by moving the tube vertically into the sockets and rotating the tube.

The louvre 12 is generally of cylindrical form and includes a plurality of longitudinal fins 20 disposed generally radially of the axis of the louvre and arranged around a central space indicated at 22. The longitudinal fins 20 are interconnected by a plurality of connecting fins 24 which are annular in shape and comprise a greater part of a circle. The connecting fins 24 lie in planes disposed transverse to the axis of the louvre. The longitudinal fins 20 and the connecting fins 24 are both provided with slots extending partially therethrough. Such interlocking of fins may be conventional as understood by those skilled in the art or they may be secured together by a novel construction forming the subject matter of my copending application, Serial No. 67,520, filed December 27, 1948, now abandoned. The connecting fins and the longitudinal fins thus occupy the same radial projection and form an annular shape occupying the greater part of a circle or cylinder. The terminal ends of the connecting fins 24 may be provided with peculiar shape as indicated at 26 for the sake of appearance and form the circumferential marginal edges of the louvre. The connecting fins are indicated generally at 24, but certain of them are given the specific reference numeral 28. Adjacent the ends of the connecting fins 28 are holes 30 (Figure 6).

40 The means for securing the louvre to the strip box comprises a pair of brackets 32. The brackets 32 are the same or symmetrical with respect to each other and a detailed description of one will suffice for both. Reference may be had to Figures 4, 5 and 6 for a complete illustration of the brackets 32. Each bracket includes a flat portion 34 adapted to fit flat against the underside of the strip box 14. The flat portion 34 is provided with laterally spaced lugs 36 which are offset upwardly (or toward the strip box) from the plane of the flat portion 34. The underside of the strip box is provided with a pair of laterally spaced notches 38 for the reception of the lugs 36. The lugs 36 are inserted in the notches 38, and the flat portion 34 is then positioned flat against the strip box. The flat portion 34 is provided with a center hole for the reception of a metal screw 40 which then is

threaded through a hole in the undersurface of the strip box; the bracket 32 is thus secured to the strip box.

Formed integral with the flat portion 34 and disposed at an angle thereto, is a portion 42 which in the present illustration extends substantially vertically. The angled portion 42 has a peculiar formation in keeping with the general appearance of the louvre, but comprises essentially, laterally extending ears 44 and 46. The ear 46 has an outer extension 48 which forms a grip for manipulating it. In this respect the two brackets 32 differ, namely, the grip portions 48 extend out the same side of the louvre whereby the brackets are not similar, but in other respects the brackets are identical. Secured in each of the ears 44 and 46 is a pin 50 which extends axially of the louvre and the pins in the two brackets 32 extend in opposite directions.

The flat portion 34 is provided with lugs 52 extending laterally outwardly from the ends. The lugs 52 are bent downwardly from the portion 34 and extend into proximity to the ears 44 and 46 and are spaced a short distance therefrom. The ears 44 and 46 are springable, that is, they may be sprung out of the normal plane of the portion 42 as indicated in Figure 6, and into engagement with the respective lugs 52 which form stops for limiting the extent of the springing movement of the ears.

The louvre is secured to the pins 50 in the ears 44 by springing those ears toward each other, aligning the holes 30 therewith and permitting the ears to spring back into position whereby the pins enter the holes. The louvre at this point is free to swing on the axis of the pins in the ears 44 which are aligned axially with respect to each other and this axis is parallel with the axis of the louvre. The louvre can then be swung to the position shown in Figure 3 whereby the light tube 18 may be inserted or removed from the sockets 60. After the light tube is inserted, the louvre is swung over the light tube to the position shown in Figure 2. The grips 48 are sprung toward each other and the louvre moved so that the holes 30 are in line therewith and then the grips 48 are released and the ears 46 spring back into their normal position and the pins enter the holes.

The lugs 52 being positioned adjacent the ears 44 and 46 serve as stop means for the ears so that the latter can not be sprung any great distance out of their normal position.

Figure 7 shows an alternate type of pin 54 secured to the ears 46. The pin 54 has an inclined surface 56 so arranged that when the louvre is swung to its closed position, the fins 28 engage the inclined surfaces 56 and spring the ears and after the pins enter the holes 30 the louvre is locked in position.

From the above it will be seen that the louvre can easily and readily be moved into and out of final fixed position. The louvre is made of simple materials almost all of which are punch press items. The louvre can be made any length to fit the various lengths of fluorescent strips.

While I have herein shown and described a preferred embodiment of my invention, manifestly it is susceptible of modification and rearrangement of the parts without departing from the spirit and scope thereof. I do not therefore wish to be understood as limiting my invention to the precise form herein disclosed, except as I may be so limited by the appended claims.

I claim:

1. A louvre for use with a light fixture with a

supporting surface having holes therein, comprising, a grille element having spaced marginal edges, a pair of brackets spaced transversely of said marginal edges, each bracket having a portion fitted flat on said supporting surface, said flat portion having an offset lug inserted in one of said holes, said flat portion having a hole for insertion of a screw therethrough and through another of the holes in the supporting surface, each bracket having a portion extending at an angle to said first portion, each angled portion having opposite ears extending laterally toward said marginal edges of said grille element, each ear having means for supporting said grille element at one point on one 15 of its marginal edges.

2. A louvre for use with a light fixture with a supporting surface having holes therein, comprising, a grille element having spaced marginal edges, a pair of brackets spaced transversely of 20 said marginal edges, each bracket having a portion fitted flat on said supporting surface, said flat portion having an offset lug inserted in one of said holes, said flat portion having a hole for insertion of a screw therethrough and through another 25 of the holes in the supporting surface, each bracket having a portion extending at an angle to said first portion, each angled portion having opposite ears extending laterally toward said marginal edges of said grille element, each ear having 30 a pin extending substantially parallel with said marginal edges, the pins longitudinally aligned extending in opposite directions, said grille element having holes in said marginal edges for receiving said pins, each ear being springable an amount at least as great as the length of its pin, and lugs on said first portion of each bracket extending into proximity with the outer ends of 35 said ears, said lugs forming stop means for limiting the springing movement of said ears.

4. A grille element for a light fixture louvre, comprising, a plurality of longitudinally extending fins spaced circumferentially around a central space and axis and having a component extending radially therefrom, and a plurality of axially 45 spaced fins lying in planes transverse to said axis and interconnecting said first fins, said connection fins having a contour such as to lie within the radial limits of said first fins, said connecting fins being arcuate in shape and extending more 50 than half a circle, and extending beyond the circumferentially outermost longitudinal fins, and the circumferential terminal ends of said connecting fins being spaced apart for the insertion of an object therethrough into said central space, 55 certain of said connecting fins having holes in said terminal ends for reception of supporting means.
